UNITED STATES PATENT OFFICE.

GEORGE QUACKENBUSH, OF BROOKLYN, NEW YORK.

ADJUSTABLE BRACKET FOR CURTAIN-POLES.

SPECIFICATION forming part of Letters Patent No. 732,652, dated June 30, 1903.

Application filed April 11, 1903. Serial No. 152,240. (No model.)

To all whom it may concern.

Be it known that I, GEORGE QUACKENBUSH, a citizen of the United States, residing at Brooklyn, in the county of Kings and State 5 of New York, have invented new and useful Improvements in Adjustable Brackets for Curtain-Poles, of which the following is a specification.

My invention relates to new and useful improvements in adjustable brackets for curtain-poles; and its object is to provide a simple and inexpensive device of this character which may be readily attached to the frame of a window and by means of which the pole 15 can be quickly moved from or toward the window, as desired.

The invention consists in providing, preferably, two arms, which are pivoted together and one of which is pivoted within a bracket 20 fastened to the frame, while the other is secured in a similar manner to a curtain-pole holder of suitable form. A rod is journaled upon the side of the window-frame and has an arm which is slidably connected to the 25 last-mentioned arm of the bracket, and by rotating this rod the arms of the bracket may be extended or retracted, as desired, to move the curtain-pole connected thereto a suitable distance from the window.

30 The invention also consists in the novel construction and arrangement of parts hereinafter more fully described and claimed, and illustrated in the accompanying drawings, showing the preferred form of my invention, 35 and in which—

Figure 1 is a perspective view showing brackets of my improved construction connected to the frame of a window. Fig. 2 is a plan view of one of the brackets having a 40 pole in position thereon, and Fig. 3 is a detail view of the joint of the arms.

Referring to the figures by numerals of reference, 1 is a bracket in which is pivotally mounted the downwardly-turned end 2 of 45 arm 3. To the other end of this arm is pivoted an arm 4, having one or more apertures therein for the reception of a stem 5, extending from a ring 6 or other suitable device adapted to engage a curtain-pole 7. A longitudinally-extending slot 8 is formed within 50 the arm 4 near the pivoted end thereof, and within this slot is slidably mounted an exten-

sion 9, which projects upward from the end of an arm 10. This arm projects laterally from the upper end of a rod 11, which is journaled in brackets 12, secured to the side of a window-frame 13.

An operating-arm 14 is arranged at the lower end of rod 11, and by swinging this arm outward it is obvious that the extension 9 will 60 ride within slot 8 and cause the arms 4 and 3 to become extended, thereby moving the pole away from the window-frame. It is obvious that by means of this device the pole can be moved to a desired distance from the window-frame, and therefore the device is especially useful where it is desired to clean windows or to place objects between the curtains and the window-frames. It will of course be understood that one of these brackets can be 70 arranged at each side of a window-frame and two short poles 7 employed, as illustrated in Fig. 1. As each pole is pivotally mounted upon its arm 4, it can, as is obvious, be swung at a desired angle to the window-frame after 75 the arms 4 and 3 have been extended. The arm 3 has a lug 15 thereon at its pivoted end adapted to contact with stops 16 on the arm 4 and prevent arm 3 from turning too far upon its pivot.

In the foregoing description I have shown the preferred form of my invention; but I do not limit myself thereto, as I am aware that modifications may be made therein without departing from the spirit or sacrificing any of 85 the advantages thereof, and I therefore reserve the right to make such changes as fairly fall within the scope of my invention.

Having thus described my invention, what I claim as new, and desire to secure by Letters 90 Patent, is—

1. A bracket for curtain-poles comprising a pivoted arm, a pole-holding arm pivoted thereto, an operating-rod and an arm thereto slidably connected to the pole-holding arm. 95

2. A bracket of the character described comprising arms pivoted together, an operating-rod and an arm thereto slidably connected to one of the arms of the brackets and adapted, when said rod is rotated, to extend or retract 100 the arms of the bracket.

3. In a bracket of the character described, the combination with arms pivoted together, of a curtain-pole holder pivoted to one of the

arms, a rod, an operating-arm extending therefrom, and a second arm extending from the rod and slidably connected to one of the arms of the bracket.

5 4. In a bracket of the character described, the combination with an arm pivoted at one end, of a second arm pivoted thereto, a curtain-pole-holding device secured to said second arm, a longitudinally-extending slide within said arm, brackets, a rod revolvably

mounted therein, an operating-arm at one end of the rod, and a second arm extending from said rod and slidably mounted within the slot.

In testimony whereof I affix my signature in presence of two witnesses.

GEORGE QUACKENBUSH.
